UNITED STATES PATENT OFFICE.

WILLIAM E. TROUTMAN, OF PITTSBURGH, PENNSYLVANIA, ASSIGNOR TO DUQUESNE STEEL FOUNDRY COMPANY, OF PITTSBURGH, PENNSYLVANIA, A CORPORATION

ANNEALING BOX.

Application filed February 14, 1925. Serial No. 8,109.

To all whom it may concern:

Be it known that I, WILLIAM E. TROUTMAN, a citizen of the United States, residing at Pittsburgh, county of Allegheny, State of Pennsylvania, have invented a new and useful Improvement in Annealing Boxes, of which the following is a full, clear, and exact description.

The present invention relates broadly to annealing boxes, and more particularly to boxes of the cast type, although certain features of the invention are adaptable for use with other types of construction.

Due to the frequent changes in temperature to which annealing boxes are subjected, and also due to the unequal temperatures to which different portions thereof are subjected at the same time, the boxes frequently tend to warp, twist and crack. One of the objects of the present invention is to provide a construction of maximum strength, adapted to permit expansion and contraction as required, and designed to prevent spreading or buckling of the sides.

In the accompanying drawings there are shown, for purposes of illustration only, preferred embodiments of the present invention, it being understood that the drawings do not define the limits of the invention as changes in the construction disclosed therein may be made without departing either from the spirit of the invention or the scope of my broader claims.

Figure 1 is a side elevation, partly broken away, of an annealing box embodying the present invention,

Figure 2 is a transverse sectional view on the line II—II of Figure 1,

Figure 3 is a vertical sectional view on the line III—III of Figure 2,

Figure 4 is a detail sectional view illustrating a slightly modified embodiment of the invention,

Figure 5 is a top plan view, partly broken away, illustrating another embodiment of the present invention,

Figure 6 is a side elevation, partly broken away, of the annealing box of Figure 5, and

Figure 7 is a transverse sectional view through the box of Figures 5 and 6, taken along the line VII—VII of Figure 6.

In carrying out the present invention there may be provided an annealing box having side walls 2, end walls 3 and a top

wall 4, all of these walls preferably being formed in one piece, as by casting. Extending entirely around the bottom of the annealing box there may be provided a thickened edge 5 serving not only as a supporting base but as a reinforcing means tending to prevent distortion of this edge from a true plane.

The walls of the box are preferably reinforced by corrugations 6 arranged in a plurality of spaced groups, each group preferably comprising a pair having an intermediate synclinal axis *aa* with an anticlinal axis *bb* on each side thereof. The bottoms of all of the corrugations preferably terminate in the plane of the inside surface of the wall in which they are provided whereby these corrugations do not interfere with the free use of the box in accordance with established practice.

The corrugations 6 preferably die out adjacent the bottom edge 5, there only being sufficient depth of corrugation adjacent this edge to permit the small amount of expansion and contraction due to the relatively lower temperatures to which this portion of the box is subjected. From the edge 5 on one side of the box the corrugations are preferably continuously extended to the edge on the opposite side thereof. For further reinforcing the side walls there may be provided laterally extending reinforcing ribs 7, these ribs preferably being alternately projected a greater distance to opposite sides of the corrugations whereby successive ribs overlap in the spaces between adjacent groups of corrugations to prevent any buckling at these points.

The end walls are each preferably provided with a single group or pair of corrugations 8 of the character before described with the transversely extending ribs 9 uniformly disposed on each side of the corrugations and preferably of a length to extend substantially the full width of the annealing box. These corrugations terminate in the edge 5 as before described and preferably also gradually die out adjacent the union of the end walls 3 with the top wall.

In usage, there is a considerable tendency for the sides of an annealing box to spread and for the top wall to fall in to a greater or lesser extent. In order to counteract both of these tendencies, they are preferably pro-

vided with trusses 10 coinciding with the synclinal axes of the groups of corrugations and formed to provide a gradually increasing cross-sectional area downwardly, as clearly shown in Figure 1. Preferably, each of these trusses has a bottom flange 11. By reference to Figure 3 of the drawings it will be noted that the bottom flanges join the sides of the annealing box in a plane below the point of union of the side walls with the top wall. This tends to directly tie the side walls together to prevent spreading thereof, and also facilitates casting the boxes as acute angles are thus eliminated.

15 In Figure 4 of the drawings there is illustrated a slightly modified form of the invention in which parts corresponding to the parts already described are designated by the same reference characters having a prime affixed thereto. In this embodiment of the invention each of the corrugations is indicated as having an interiorly projecting rib or flange 12' coinciding with the anticlinal axis of the corrugation with which it cooperates. These ribs or flanges further tend to reinforce and stiffen the side walls without interfering with the flexibility imparted to the wall, from a standpoint of expansion and contraction, by the corrugations.

30 In the form of the invention shown in Figures 5, 6 and 7, there is utilized the same general arrangement of reinforcing corrugations 16 both for the side and end walls of the annealing box. I have found, however, that in some cases it is desirable to substitute for the reinforcing ribs 7 a modified system of ribs 17 which die out adjacent the anticlinal axes of each of the corrugations instead of extending continuously theracross. In this manner, greater flexibility from a standpoint of expansion and contraction is permitted without material distortion of the corrugations. The ribs 17 may be connected by vertically extending ribs 18 which also tend to prevent bulging or sagging of the sides.

45 The advantages of the present invention arise from the provision of an annealing box having reinforcing means preventing buckling, warping, twisting or spreading of the walls without interfering with the use of the box as is now customary in the art.

I claim:

- 50 1. An annealing box, having its side walls formed with reinforcing corrugations arranged in a plurality of spaced groups.
- 55 2. An annealing box, having its side walls formed with reinforcing corrugations arranged in a plurality of spaced pairs.
- 60 3. An annealing box, having its side walls formed with vertically extending reinforcing corrugations arranged in a plurality of

spaced groups, the corrugations in opposite sides being extended across the top wall of the box.

65 4. An annealing box, having reinforcing corrugations so grouped as to form at least one pair of reinforcing corrugations in each wall thereof.

5. An annealing box, having at least one pair of reinforcing corrugations formed in each wall thereof, and reinforcing ribs cooperating with certain of said corrugations.

6. An annealing box, having a pair of corrugations formed in the top wall thereof, and a reinforcing truss projecting downwardly from the top wall and located on the synclinal axis of said pair of corrugations.

7. An annealing box, having its top wall formed with reinforcing corrugations arranged in a plurality of spaced pairs, and a reinforcing truss cooperating with each pair of corrugations.

8. An annealing box, having vertically extending corrugations in its side and end walls, said corrugations being arranged in pairs, and reinforcing ribs extending transversely of said corrugations.

9. An annealing box, having vertically extending corrugations in its side and end walls, said corrugations being arranged in pairs, and reinforcing ribs extending transversely and parallel to said corrugations.

10. An annealing box, having vertically extending corrugations in its side and end walls, said corrugations being arranged in pairs, and reinforcing ribs extending transversely and parallel to said corrugations, the transversely extending reinforcing ribs on the side walls of the annealing box extending in overlapping relationship in the spaces between adjacent pairs of corrugations.

11. In an annealing box, an inclosing wall having a pair of reinforcing corrugations therein, and a reinforcing rib projecting inwardly along the anticlinal axis of each corrugation.

12. An annealing box, having reinforcing corrugations grouped to form at least one pair of reinforcing corrugations in each side wall thereof.

13. An annealing box, having reinforcing corrugations grouped to form at least one pair of reinforcing corrugations in each end wall thereof.

14. An annealing box, having vertically extending corrugations in its side and end walls, said corrugations being arranged in pairs, and reinforcing ribs extending transversely of said corrugations.

In testimony whereof I have hereunto set my hand.

WILLIAM E. TROUTMAN.
